Primary Examiner — Robin V Webster
Assistant Examiner — Rachel Voorhies

(57) **CLAIM**

The ornamental design for a knife handle and bolster, as shown and described.

DESCRIPTION

FIG. 1 is a left side perspective view of the knife handle and bolster, showing my new design.

FIG. 2 is a left-side view thereof, the right-side being a mirror image.

FIG. 3 is a top view thereof.

FIG. 4 is a bottom view thereof.

FIG. 5 is a rear view thereof; and,

FIG. 6 is a front view thereof.

The broken lines shown in the drawings illustrate the environment of the claimed design and form no part thereof.

1 Claim, 3 Drawing Sheets
